UNITED STATES PATENT OFFICE.

RAOUL J. GRUENBERG, OF SAN FRANCISCO, CALIFORNIA, ASSIGNOR TO THE PAR-AFFINE COMPANIES, INC., OF SAN FRANCISCO, CALIFORNIA, A CORPORATION OF DELAWARE.

BOX-GLUING MACHINE.

Application filed May 29, 1922. Serial No. 564,289.

To all whom it may concern:

Be it known that I, RAOUL J. GRUENBERG, a citizen of the United States, residing at San Francisco, in the county of San Francisco, State of California, have invented a new and useful Box-Gluing Machine, of which the following is a specification in such full and clear terms as will enable those skilled in the art to construct and use the same.

This invention relates to a machine for gluing the tabs of paper or fibre board boxes and its object is to produce a machine which is capable of being constructed at very reasonable cost which will enable the user to assemble boxes rapidly and efficiently, the gluing machine being so arranged as to exert sufficient pressure upon the glued box tabs to insure holding them properly when once glued.

Another object of the invention is to provide a machine which will be substantially automatic in operation, the operator merely depressing a foot lever which causes the gluing rolls to pass over two of the box tabs after which a presser foot causes the short box tab at the end of the box to be pushed into contact with the first two tabs with sufficient force to insure securing them together.

Another object of the invention is to provide a machine which is capable of being adjusted laterally to permit wider or narrower boxes being glued thereby, the gluing rolls and the presser feet being both moved toward or away from the center of the machine to thereby equalize the operation on both of the tabs to be glued.

Other objects of the invention will appear as the description proceeds.

An embodiment of the invention is shown in the accompanying drawings in which the same reference numeral is applied to the same portion throughout, but I am aware that there may be modifications thereof.

Fig. 1 is a front elevation of the complete machine.

Fig. 2 is a vertical sectional view of the complete machine on the line 2—2 of Figure 50 1.

Fig. 3 is a view of the upper portion of the machine showing its appearance from the side.

Fig. 4 is a side elevation of one of the gluing tab tables separate from the machine. 55

Fig. 5 is a front elevation of one of the gluing tab tables separate from the machine.

Fig. 6 is a view of a portion of the foot pedal illustrating its operation with respect to the gluing roller operating link. 60

Figures 7 and 8 are detail views showing the operation of the tab folding mechanism.

Fig. 9 is a plan view of the upper portion of the machine, the base and foot pedal being omitted, and 65

Fig. 10 a view in elevation of the machine looking from the back, only the upper portion being shown. 70

The machine has two base plates 1 and 2 which are connected to two angle bars 3 and 4 to form the base of the machine. The angle bars 3 and 4 support two vertically extending angle bars 5 and 6, the latter bars 75 being connected to the base bars 3 and 4 with gusset plates 7 and 8 to give additional strength.

At the upper end the side posts 5 and 6 are connected together by an angle bar 9. 80 The vertically movable channel bar 9' forms the support for the two presser tables 10 and 11. In order to give the frame rigidity two diagonal braces 12 and 13 are connected to the posts 5 and 6, while the channel bar 9' is movable vertically therein a short distance as will be later explained. 85

The tab folding table has two projecting flanges 14 and 15 the upper of which has a depending hook 16 to hold it in engagement with the channel bar. These flanges enable the tab folding table to be held in position during adjustment thereof and bolts 17 and 18 operative through slots 19 and 20 of the channel bar afford the means for fixing the tab folding tables in any given position. 90

The channel bar 9' has angles 21, 22 secured thereto at its ends, which angles are connected to four links 23, 23', 24, 24' loosely mounted on two shafts 25, 26. The channel bar 9' when not raised by the operator rests upon two short angle bars 91, 92 secured to the posts 5 and 6. The shafts 25, 26 are journaled in four bearings 27, 27', 28, 28' on the two posts 5 and 6. Depending 100

from the center of the channel bar 9' is a yoke 29 which is secured to the channel bar by means of a bolt 30. This yoke is connected to a link 31 by means of a bolt 32, the link being slotted to allow a certain movement of the operating apparatus prior to the vertical movement of the channel bar.

Mounted on two blocks 34, 35 at the upper end of the posts 5 and 6 are two bearings 37, 38 in which is journaled a shaft 39. The shaft 39 has two presser feet 40, 41 mounted thereon, said presser feet being movable longitudinally along the shaft to give any desired adjustment between the two bearings 37, 38. This shaft also has an arm 42 mounted thereon which is pivotally connected to a link 43 connected pivotally at its other end to an arm 44 on the shaft 25.

The shaft 25 also has an arm 45 thereon which has a pin for pivotally connecting it to the upper end of a link 46, said link being pivotally connected at its lower end at 47 to the foot lever 48. The foot lever 48 is pivotally connected at one end to a shaft 49 extending between the two angle plates 3 and 4. It also has two links 50, 51 pivotally connected thereto, which links are slotted at their upper end to receive an arm 52 on the shaft 53. The arm 52 is carried by a boss on the shaft 53, which boss also has an arm 54 thereon pivotally connected by means of a pin 55 to the lower end of the link 31.

The foot lever has a pin 56 for engaging a hook on the lower end of the rod 57, and said hook is so shaped as to engage a pin 58 on a short post 59, thereby disengaging the rod 57 from the pin 56 when the glue rollers have passed over the end tabs of the box.

Secured on the frame members 5 and 6 are two cleats 60, 61 in which a horizontally extending bar 62 is vertically movable. This bar is slotted to provide for an adjustment of two upperly extending links 63, 64, which links are connected at their upper ends to the short end of the glue roller operating arms 65, 66. These arms are journaled on shafts 67, 68 each of which is supported by the bearings 69, 70 formed on the lower part of the tab presser table.

Each tab presser table carries a glue pot as indicated at 72, 73 and each glue pot has a feed roller therein as indicated at 74, 75. The feed rollers have the small gears 76, 77 thereon in mesh with large gears 78, 79, duplicates of each other.

The gears 78, 79 are journaled on the back of the glue receptacle and they each have a slotted arm 80 pivotally mounted on the gear shaft, which slots have rods 81, 82 extending there into, and said rods 81, 82 are secured at their upper ends to arms 83, 84 on the shaft 39. Pawls 80' connect the arms 80 with and drive the wheels 78, 79.

At the upper ends the gluing rollers have two arms 85, 86 connected thereto to extend in a substantially horizontal direction, a shaft 87 connecting the arms 85 and arms 85' and carrying a spring 88 to hold the rollers down against the box tab with sufficient force to press it down when the gluing rollers are pressed against the same.

Angle plates 91, 92 form a support to limit the downward movement of the channel bar and tab supporting table, and they form the support for the glue receptacles. A spring 93 connected to the link 57 restores the gluing rollers and the arms carrying them to their position as shown in Figure 1, a stop 94 preventing the link 57 from being drawn too far rearwardly by the spring.

The operation of the apparatus is as follows: The operator sits in front of the machine and places the boxes in front of the two tables 10 and 11 with the end tabs all extending upwardly, thereupon the foot lever 48 is depressed. The first action is to push the two pairs of gluing rollers inwardly against the end flaps of the box folding them on the top of the tables 10 and 11. When the foot lever has been depressed sufficiently the pin 58 will kick it loose from the pin 56 thereby allowing the spring 93 to restore it to the position shown in Fig. 2.

At the moment of release of the link 57, the link 46 will cause the presser feet 40, 41 to be pushed against the outer end flap of the box thereby pushing it over the top of the two glued end flaps and when the two presser feet have been moved to a vertical position, the link 31 will cause the channel bar 9' and attached parts to be raised and bring the tables 10 and 11 into contact with the presser feet 40, 41 with a toggle joint effect due to the fact that the arm 54 and link 31 will be at that moment substantially in line vertically, the slots in the link 31 being arranged of such length as to permit this desired toggle joint effect to give great pressure upon the box tabs at that moment.

As soon as the foot pedal 48 is released the weight of the channel bar 9' and tab supporting tables 10 and 11 is sufficient to restore the apparatus to the position to receive another box. At the same time the links 81, 82 will cause the gears 78, 79 to rotate the glue rollers 74, 75 a sufficient number of times to feed the desired amount of glue to the rollers 89.

Just above each of the tables 10 and 11 and at the back of them there are two upwardly projecting lugs 10', 11' which carry threaded rods as indicated in Figure 2 at 10'', which rods bear against projecting lugs 45' on the corresponding arms, the object being to prevent said arms from moving too far back when the front tab of the box is being forced down.

What I claim is as follows, but various

modifications may be made in the construction shown in the drawings and above particularly described form, within the purview of my invention.

5 1. A box forming machine comprising a pair of end flap supports, rollers to push two of the side flaps of a box blank over said supports, means to supply said rollers with glue, means to thereafter push the bottom flap over the two glued flaps, and means to press all of the flaps together to secure them together.

10 2. A machine for forming boxes comprising a support for the box end tabs, laterally movable rollers for pushing two of the tabs over said support and for gluing them, swinging arms moving at a right angle to the gluing rollers for pushing one of the tabs over the top of two of the others, and means to bring all of the tabs together under considerable pressure to effect the gluing of the box ends.

15 3. In a box gluing machine a support for the end tabs of a box, laterally movable arms carrying gluing rollers for pushing two of the tabs over said support, other arms movable at right angles to the first arm for pushing one tab over the glued tabs, and means to raise said support to push the box end tabs placed thereover into contact with each other for securing them together.

20 4. A box forming machine comprising a support, means to push two box tabs over said support, arms movable at right angles to the first mentioned means for pushing one of the box end tabs over the top of two others, and means to bring the box end tabs together under considerable pressure for securing them together.

25 5. In a box gluing machine a support, a pair of arms movable toward and away from each other to push two box tabs over the top of said support, means to supply said arms with glue, means to push a short tab of the box over the top of two others, and a foot pedal for raising the support into contact

with two of said arms to bring the box end tabs together to be glued.

30 6. In a box gluing machine supports for the end tabs of a box, laterally movable arms to push the side tabs of a box toward each other and to place glue thereon, and means to push the bottom end tab of a box over the other two end tabs and press the tabs together to complete the box.

35 7. In a box gluing machine a support for the end tabs of a box, laterally movable arms for pushing two of the side tabs toward each other to form the inside portion of the box end and to place glue thereon, other arms movable in a plane at right angles to the first arms to push another box tab over the top of the first two tabs, and means to compress all of the tabs for securing them in contact with each other.

40 8. In a box gluing machine the combination with a pair of laterally adjustable supports of a pair of arms adjustable with said supports and movable laterally to push a pair of box end tabs toward each other, rollers for supplying said arms with glue whereby the tabs are glued at the same time, a pair of adjustable arms for pushing a bottom tab over the top of the other two tabs when the gluing roller arms are retracted, and means to raise the supports to press the tabs together to form the complete box.

45 9. A box gluing machine comprising a pair of supports, a pair of arms carrying gluing rollers movable toward and away from each other, means to supply said rollers with glue so that as two of the box tabs are pushed down upon said supports they will be supplied with glue at the same time, swinging arms for pushing a bottom tab over the top of the other two tabs, means to lift said supports to press all of the tabs tightly together, and a foot pedal for carrying out the complete cycle of operations.

50 In testimony whereof I have hereunto set my hand this 17th day of May, A. D. 1922.

RAOUL J. GRUENBERG.
